TIE CLASP OR SIMILAR ARTICLE

Rodney Ettman, Woodmere, N. Y.

Application May 7, 1948, Serial No. 146,208

Term of patent 3½ years

(Cl. D17—10)

To all whom it may concern:

Be it known that I, Rodney Ettman, a citizen of the United States of America, and a resident of Woodmere, Long Island, New York, have invented a new, original, and ornamental Design for a Tie Clasp or Similar Article, of which the following is a specification, reference being had to the accompanying drawings, forming a part thereof, in which

Figure 1 is a front elevational view of a tie clasp, or similar article, showing my new design, Fig. 2 is a side elevational view thereof; and Fig. 3 is an end elevational view.

I claim:

The ornamental design for a tie clasp or similar article, as shown.

RODNEY ETTMAN.
